UNITED STATES PATENT OFFICE.

LOUIS BECKER NEWELL, OF BALTIMORE, MARYLAND, ASSIGNOR TO CARR-LOWREY
GLASS COMPANY, OF BALTIMORE, MARYLAND.

BOTTLE.

1,399,313.

Specification of Letters Patent.

Patented Dec. 6, 1921.

Application filed April 9, 1921. Serial No. 459,830.

To all whom it may concern:

Be it known that I, LOUIS B. NEWELL, a citizen of the United States, residing at 3 Augusta Ave., Baltimore, in the State of Maryland, have invented a new and useful 5 Bottle, of which the following is a specification.

This invention relates to bottles, one of its objects being to provide a container of this 10 character especially designed for holding perfume.

One of the objects of the invention is to provide one surface of the container with a frosted or translucent finish, the same being intersected by crossed transparent ribs while formed on the translucent surface but intersected by the transparent ribs is the representation of a flower or other object so that the effect of a flower or the like growing upon a lattice is produced.

A further object is to provide a bottle having a transparent surface opposite to that on which the design appears so that said design can be viewed by looking through the 25 bottle and through the colored liquid that may be contained therein, the same result as before explained being thus secured with the exception that the appearance is greatly enhanced by the color imparted to the design 30 by the liquid within the bottle.

A further object is to provide a container the smooth transparent surface of which can be used as a magnifying lens whereby the design upon the far wall of the container is 35 distorted or magnified and thus rendered more apparent to the observer than would otherwise be the case.

With the foregoing and other objects in view which will appear as the description 40 proceeds, the invention resides in the combination and arrangement of parts and in the details of construction hereinafter described and claimed, it being understood that, within the scope of what is claimed, changes in the 45 precise embodiment of the invention shown can be made without departing from the spirit of the invention.

In the accompanying drawings the preferred form of the invention has been shown.

50 In said drawings—

Figure 1 is an elevation of the bottle showing the flat wall thereof carrying the design.

Fig. 2 is an elevation of the opposite side of the bottle and showing the transparent

surface, the magnified design being seen 55 therethrough.

Fig. 3 is a transverse section through the bottle.

Referring to the figures by characters of reference 1 designates a bottle of any desired size and proportions and one wall of the bottle has its outer surface polished and cut, as shown at 2, the inner surface of this wall being preferably convexed as ordinarily 60 and as shown at 3 so that the wall thus 65 forms a plano-convex lens. Both surfaces of this wall are transparent but all of the remaining walls of the container are preferably frosted or otherwise rendered translucent. The outer surface of the opposed 70 wall of the bottle is formed with intersecting outstanding ribs 4 the free longitudinal edges of which are transparent while the remaining portions of the surface between these ribs are frosted. A suitable design, 75 such as the representation of a flower, a portion of a vine, or the like, such as indicated at 5, can be formed on this frosted or translucent wall of the bottle, the design being intersected by the transparent ribs as shown 80

particularly in Fig. 1. Thus it will be seen that when the bottle is viewed, the light rays by passing straight through the transparent ribs 4 will cause said ribs to stand out clearly upon the frosted background so as to 85

have the appearance of a lattice work behind which the figure 5 is disposed. This impression is greatly enhanced by viewing the design through the magnifying and transparent wall of the bottle. If the bottle 90 is filled with a colored liquid the color of the liquid will be imparted to the design and owing to the construction and arrangement of the parts the bottle when viewed through the transparent surface 2 is rendered 95 especially attractive. Obviously by providing the transparent ribs 4 said ribs will stand out clearly so as to present the appearance of a lattice, this result being also especially noticeable when the colored liquid 100

contents of the bottle are seen through the transparent ribs when the wall carrying the design is nearest the observer. Thus it will be seen that the bottle is rendered especially attractive when viewed from either side, the 105 colored ribs 4 standing out prominently and being shown extending across the figure 5 when the bottle is viewed as shown in Fig.

1 while the said ribs as well as the entire
design are distorted and enlarged when
viewed through the magnifying wall of the
bottle, the transparent ribs under these con-
5 ditions continuing to stand out clearly upon
the background containing the figure 5.

It is to be understood that the arrange-
ment of bars and the figure disclosed back of
the bars can be changed without departing
10 from the scope of the claims.

What is claimed is:—

1. A bottle including a translucent wall
containing a design and transparent ribs
extending across said wall and intersecting
15 the design.

2. A bottle including a translucent wall
containing a design and transparent ribs
extending across said wall and intersecting
the design, and a transparent wall opposite

the design carrying wall through which the 20
contents of the bottle and said design car-
rying wall are visible.

3. A bottle including a translucent wall
containing a design and transparent ribs
extending across said wall and intersecting 25
the design, said ribs adapted to be colored
by liquid contained in the bottle, thereby
to stand out with increased prominence with
respect to the design, and a transparent wall
opposite the design carrying wall through 30
which the contents of the bottle and said
design carrying wall are visible, said trans-
parent wall constituting a plano-convex lens
for magnifying the design carrying wall.

In testimony that I claim the foregoing as 35
my own, I have hereto affixed my signature.

LOUIS BECKER NEWELL.
